UNITED STATES PATENT OFFICE

THEODORE E. LOUIS, OF BERKELEY, CALIFORNIA

DESIGN FOR A SIGN

Application filed March 14, 1932. Serial No. 43,194. Term of patent 7 years.

To all whom it may concern:

Be it known that I, THEODORE E. LOUIS, a citizen of the United States, residing at Berkeley, in the county of Alameda and State of California, have invented a new, original, and ornamental Design for Signs, of which the following is a specification, reference being had to the accompanying drawing, forming a part thereof.

The figure is a face view of my new sign.

The particular form of the wording, involving lettering, is considered a part of my new design.

The opposite side of the sign is a substantial duplication of the side shown.

I claim:

The ornamental design for a sign as shown and described.

THEODORE E. LOUIS.
